UNITED STATES PATENT OFFICE.

CHARLES E. PECK, OF HARTFORD, CONNECTICUT, ASSIGNOR TO UNITED STATES TIRE COMPANY, A CORPORATION OF NEW YORK.

DESIGN FOR A STICK-PIN.

52,552.

Specification for Design.

Patented Oct. 8, 1918.

Application filed June 5, 1917. Serial No. 173,051. Term of patent 3½ years.

To all whom it may concern:

Be it known that I, CHARLES E. PECK, a citizen of the United States, residing at Hartford, county of Hartford, and State of Connecticut, have invented a new, original, and ornamental Design for Stick-Pins, of which the following is a specification, reference being had to the accompanying drawing, forming part thereof.

The figure is a front elevational view of a stick pin showing my new design.

I claim:

The ornamental design for a stick pin, as shown.

Signed at Hartford, Connecticut, this 28th day of May, 1917.

CHAS. E. PECK.
